UNITED STATES PATENT OFFICE

JEAN B. DAUDELIN, OF FALL RIVER, MASSACHUSETTS

SHUTTLE

Application filed August 13, 1929. Serial No. 385,617.

My present shuttle is an improvement upon earlier loom shuttles of the automatically threading type heretofore patented by me, particularly in respect to the threading feature, and aims to provide that certainty and positiveness of threading action regardless of the direction of travel of the shuttle at the moment of threading, so necessary in a shuttle of this type.

10 Another feature consists in the design and structure of the shuttle itself to the end that the thread will be positively controlled, tensioned, and guided during the run of the shuttle, all in a construction requiring such slight 15 change of existing shuttle structure as to be capable of embodiment therein at the minimum cost.

These and various other features of utility and advantage are secured in the shuttle 20 forming the subject matter of my present invention, the construction and operation of which is described and illustrated in the accompanying specification and drawings. In the drawings:

25 Fig. 1 is a fragmentary plan view at the threading end of a shuttle of standard type equipped in accordance with my invention and showing the shuttle threaded.

Fig. 2 is a side view thereof.

30 Fig. 3 is a view similar to Fig. 1, partially in horizontal plan section.

Fig. 4 is a cross section on the line 4—4, of Fig. 3 and

Fig. 5 is a view similar to Fig. 1, but 35 showing a slight modification, and

Fig. 6 shows a further modification in which the anchoring end of the pin serves as a snubbing post.

The shuttles shown are of standard manufacture and include a body 1 formed to provide a bobbin chamber 2 in which is mounted a bobbin 3 having a filling 4 wound thereon.

Forwardly of the bobbin chamber, the shuttle body extends as a threading end, indicated generally at 5, having the usual threading slot which consists of a longitudinal slot portion 6 in its top wall connecting adjacent the tip of the shuttle with the downwardly and rearwardly extending slot portion 7 in the side wall of the shuttle, said

rearwardly extending slot portion opening into the shuttle eye 8, which is a simple bore extending transversely across the shuttle at substantially the rear end of the longitudinal slot 6 and beneath the same.

In threading, the filling 3 from the bobbin is laid from above in said longitudinal slot 6, as indicated in dotted lines Fig. 1, and is drawn through said rearwardly extending slot 7 until it is lodged in said eye 8, after which the filling runs directly from the bobbin through the eye.

In order properly to guide and direct the filling both during the threading action and subsequently in the run of the shuttle, I place adjacent the threading slot and in the eye certain instrumentalities which so combine and cooperate with each other as to secure this result, regardless of the direction of travel of the shuttle at the moment that the 70 threading action occurs.

In accordance with my present invention I lodge in the body of the shuttle adjacent the threading slot a combination thread guide and deflector member 9. This may consist of a simple pin or length of bendable wire, which in the form of my invention shown in Figs. 1 to 4 inclusive is driven as a straight pin from front to rear through the overhanging nosing portion 10 of the shuttle defined by the slots 6 and 7 and eye 8 and is then bent at substantially right angles upon itself to provide at its rear end a downwardly extending substantially vertically disposed anchoring portion 11.

The forward end 12 of the pin 9 is exposed beyond the nosing portion 10 of the shuttle as a thread deflecting portion disposed at substantially the juncture of the slots 6 and 7 and past which the thread is adapted to be 90 drawn in threading the shuttle.

This exposed portion 12 of the pin or wire is preferably arranged diagonally with respect to the longitudinal slot 6, but since the material of the pin is bendable, may be bent 95 to any desired angle. If desired, the wall of said slot opposite the terminus of said pin or wire 9 may be undercut slightly as indicated at 13 to insure proper clearance of the thread.

In the modification shown in Fig. 5, the construction and location of the pin or wire 9 is otherwise the same as in Figs. 1 to 4, except that the wire is exposed on top of the nosing 10 rather than being concealed within said nosing for the major portion of its length as in Figs. 1 to 4.

In both forms, the function of the pin or wire is to deflect the thread in the threading action of the shuttle from the slot 6 into the slot 7, as well as to prevent improper escape of the thread after the shuttle has been threaded, by ballooning or the like. In the performance of its deflecting function, the position of the deflective portion 12 at the forward end of the slot 6 and in substantially the longitudinal axis of the shuttle is well adapted to accomplish this result, since the tip of the shuttle is the logical point at which to turn the thread from the slot 6 into the slot 7 and in the performance of its second function, such position brings the portion 12 over the forward end of the slot 7 as an overlying barrier past which the thread cannot escape by a direct upward lifting action.

Cooperating with the member 9 is the eyepiece proper of the shuttle. This eye piece is a simple coil or turn 14 of wire or the like lining the outer end of the shuttle eye 8. It is preferably made in one piece to provide an anchoring portion 15 which is driven into the side wall of the shuttle above the rear end of the slot 7 and forwardly of the eye 8, the fore end of the turn or coil 14 extending transversely across the shuttle above the eye as a shank 15¹ which not only assists to fix the eyepiece in position in the eye, but also serves as a barrier to prevent improper escape of the thread from the eye, after the shuttle has been threaded, by an upward lifting movement which might cause the thread to lift into the vertical threading slot 6.

After the shuttle has been threaded the filling runs directly from the bobbin into the eye, being turned thereto by a snubbing post 16 which is driven vertically into the shuttle from below. If desired, the eye may be filled with yarn or the like, as indicated at 17, to tension the thread passing therethrough.

It will be noted that in addition to its guiding and barrier functions, the pin or wire introduces a factor of strength into the nosing 10.

As illustrated in Fig. 6 instead of driving a separate pin to form the snubbing post 16, the downturned end 11 of the wire 9 may be so deflected as to occupy the position ordinarily occupied by the separate and independent post 16 in which event such end 11 would act as the snubbing post as well as the anchorage for the wire. In such event the combination snubbing post and anchoring pin portion 11 of the guide member 9 is first

bent downwardly at substantially right angles to the guide member, and such member is thereafter driven into the wood of the shuttle from above. When so driven said member is embedded in the upper surface of the shuttle nose.

Various other modifications in the design and construction of my device may obviously be resorted to, all without departing from the spirit of my invention if within the limits of the appended claims.

What I therefore claim and desire to secure by Letters Patent is:

1. In a shuttle having a bobbin chamber and a threading eye and having a threading slot presenting a longitudinal portion extending forwardly of the shuttle from said chamber, and a downwardly and rearwardly extending portion connecting said forwardly extending portion with the outer end of said eye, a guide member lodged in the shuttle body inwardly of said threading eye and having its other end extending as a free bendable portion disposed adjacent the juncture of said slots with each other and in overlying relation thereto and effective in the threading action of the shuttle to deflect the thread from said longitudinal slot into said rearwardly extending slot and effective during the run of the threaded shuttle to prevent improper escape of the thread from said rearwardly extending slot.

2. In a shuttle having a bobbin chamber and a threading eye and having a threading slot presenting a longitudinal portion extending forwardly of the shuttle from said chamber, and a downwardly and rearwardly extending portion connecting said forwardly extending portion with the outer end of said eye, a guide member lodged in the shuttle body inwardly of said threading eye and having its other end extending as a free bendable portion disposed adjacent the juncture of said slots with each other and in overlying relation thereto and effective in the threading action of the shuttle to deflect the thread from said longitudinal slot into said rearwardly extending slot and effective during the run of the threaded shuttle to prevent improper escape of the thread from said rearwardly extending slot, the rear end of said guide member being driven into the shuttle body as a downwardly extending anchoring pin.

3. In a shuttle having a bobbin chamber and a threading eye and having a threading slot presenting a longitudinal portion extending forwardly of the shuttle from said chamber, and a downwardly and rearwardly extending portion connecting said forwardly extending portion with the outer end of said eye, a guide member lodged in the shuttle body inwardly of said threading eye and having a portion disposed adjacent the juncture of said slots with each other and in

overlying relation thereto and effective in the threading action of the shuttle to deflect the thread from said longitudinal slot into said rearwardly extending slot and effective 5 during the run of the threaded shuttle to prevent improper escape of the thread from said rearwardly extending slot, the rear end of said guide member being driven into the shuttle body as a downwardly extending 10 anchoring pin constituting a snubbing post past which the thread is drawn during the run of the shuttle.

4. In a shuttle having a bobbin chamber and a threading eye and having a threading slot presenting a longitudinal portion extending forwardly of the shuttle from said chamber and a downwardly and rearwardly extending portion connecting said forwardly extending portion with the outer end of 20 said eye, a guide member anchored inwardly of said threading eye and extending longitudinally of the shuttle between the eye and the juncture of the threading slots with each other and terminating at its forward end in a free 25 bendable portion disposed adjacent the juncture of said threading slots and in overlying relation thereto and effective in the threading action of the shuttle to deflect the thread from said longitudinal slot into said 30 rearwardly extending slot and effective during the run of the threaded shuttle to prevent improper escape of the thread from said rearwardly extending slot.

5. In a shuttle having a bobbin chamber 35 and a threading eye and having a threading slot presenting a longitudinal portion extending forwardly of the shuttle from said chamber and a downwardly and rearwardly extending portion connecting said forwardly extending portion with the outer end of said eye, a guide member anchored inwardly of said threading eye and extending longitudinally of the shuttle between the eye and the juncture of the threading slots with each 40 other and terminating at its forward end in a free bendable portion disposed adjacent the juncture of said threading slots and in overlying relation thereto and effective in the threading action of the shuttle to deflect 45 the thread from said longitudinal slot into said rearwardly extending slot and effective during the run of the threaded shuttle to prevent improper escape of the thread from said rearwardly extending slot, the rear end 50 of said guide member being driven into the shuttle body as a downwardly extending anchoring pin.

6. In a shuttle having a bobbin chamber and a threading eye and having a threading 55 slot presenting a longitudinal portion extending forwardly of the shuttle from said chamber and a downwardly and rearwardly extending portion connecting said forwardly extending portion with the outer end of said eye, a guide member anchored inwardly of

said threading eye and extending longitudinally of the shuttle between the eye and the juncture of the threading slots with each other and terminating at its forward end in a free bendable portion disposed adjacent 70 the juncture of said threading slots and in overlying relation thereto and effective in the threading action of the shuttle to deflect the thread from said longitudinal slot into said rearwardly extending slot and effective 75 during the run of the threaded shuttle to prevent improper escape of the thread from said rearwardly extending slot, the rear end of said guide member being driven into the shuttle body as a downwardly extending anchoring pin, the wall of the longitudinal threading slot adjacent the forward end of 80 said guide member being slightly undercut to insure thread clearance.

7. A guide for a shuttle having an eye and a threading slot communicating therewith, comprising a member having one end disposed adjacent said threading slot and constituting a deflecting surface past which the thread is drawn in threading the shuttle 85 and having its opposite end anchored in the body of the shuttle inwardly of said eye and constituting a snubbing post past which the thread is drawn during the run of the shuttle. 90

8. A guide for a shuttle having an eye and a threading slot communicating therewith, comprising a wire disposed substantially longitudinally of the shuttle and having its rear end anchored in the shuttle inwardly of said eye and its forward end extending as a free bendable portion disposed at an angle to a portion of the threading slot 100 and constituting a deflecting surface past which the thread is drawn in threading the shuttle, and having its rear end disposed as 105 a downwardly extending anchoring pin fastened in the body of the shuttle.

9. A guide for a shuttle having an eye and a threading slot communicating therewith, comprising a wire disposed substantially longitudinally of the shuttle and having its forward end extending at an angle to a portion of the threading slot and constituting a deflecting surface past which the thread is drawn in threading the shuttle, and having its rear end disposed as a downwardly 110 extending anchoring pin fastened in the body of the shuttle, and constituting a snubbing post past which the thread is drawn during 115 the run of the shuttle. 120

In testimony whereof I affix my signature.
JEAN B. DAUDELIN.
